UNITED STATES PATENT OFFICE.

ROBERT D. BAKER, OF DETROIT, MICHIGAN.

PAVING APPARATUS.

1,089,182.

Specification of Letters Patent.

Patented Mar. 3, 1914.

Application filed April 2, 1913. Serial No. 758,422.

To all whom it may concern:

Be it known that I, ROBERT D. BAKER, a citizen of the United States, residing at Detroit, in the county of Wayne and State 5 of Michigan, have invented certain new and useful Improvements in Paving Apparatus, of which the following is a specification.

This invention relates to paving apparatus; and it has to do more particularly 10 with apparatus for forming and placing armored joints in concrete pavements; and it comprises means for receiving and rigidly holding the plates or similar armoring members forming the paving joint, and for 15 supporting the members thus held in a pre-determined position relative to the road bed on which the concrete pavement is to be laid, the supporting means being detachable from the joint members after paving 20 material has been placed in final position around said armoring members; all as more fully hereinafter set forth and as claimed.

In laying concrete pavements comprising mixtures of cement, sand, broken stone, etc., 25 with or without the addition of other materials such as asphalt and the like, it is necessary in practice to provide joints at intervals in the pavement to provide for expansion and contraction. If such joints are 30 not provided the pavement is apt to crack or heave as the result of contraction or expansion due to temperature changes. In providing such expansion joints it has been found necessary to protect the edges of the 35 joints, as for example by facing the joints with iron or steel plates, in order to prevent undue wear and crumbling away of the joint edges when the pavement is subjected to the wear of traffic. Unless the pavement 40 points are thus armored in some way, the corners of the joints become worn away by the constant pounding of traffic, and depressions or ruts are prone to form at these localities, thus destroying the desired uniformity and smoothness of the roadway.

One method of armoring concrete pavement joints which has found considerable application in practice, is to arrange parallel iron or steel plates embedded and anchored, as to their non-adjacent sides, in the concrete materials of the pavement, and their adjacent sides being spaced apart a short distance to allow for the necessary expansion and contraction of the pavement 55 sections. It is usually advantageous to fill

the space between the plates with felt, paper, pitch, asphalt, etc., which, while preventing the access of undesirable materials into the joint, is itself sufficiently yielding in character not to interfere with the expansion and contraction of the pavement. The upper edges of these plates should be as nearly flush with the surface of the finished roadway as it is possible to place them. Obviously if the plates project above the 60 roadway, they will form irregularities in the pavement which are extremely undesirable; while on the other hand, if they terminate below the surface of the pavement, the unprotected edges of the joints 70 above them will wear away to form ruts as before described. If the plates be made of metal having the proper degree of softness, and if the plates be so placed that their upper edges are just flush with the surface 75 of the finished pavement, the concrete pavement and the exposed edges of the armor plates wear down together at a practically uniform rate, the smoothness of the originally finished pavement being thus preserved until the pavement is worn out.

In practice it is exceedingly difficult to place the armor plates in just the proper position required to give the most satisfactory results in the finished pavement. It 80 has been customary heretofore to set the plates on edge on the prepared road bed and transversely thereof, the plates being spaced apart as by temporary steel division plates, asphalt felt, paper, or the like, and 85 clamped together into a rigid assemblage. This assemblage is then lined up across the roadbed by means of stakes driven into the roadbed on both sides of the assemblage in staggered or alternating arrangement, and 90 supported from below by the ground, by blocking up, or by stakes driven into the ground, these various supporting means being adjusted until the upper edges of the armor plates are found by comparison with 95 a line of reference of some kind, such as a cord stretched across the road, to be at just the proper elevation. The concrete is then placed on either side of the pair of armor plates, prongs or projections from the plates 100 being generally provided to insure proper anchorage for the plates. The concrete having been placed around on both sides of the armor joint to the proper depth and properly tamped, it is then smoothed off 110

flush with the upper edges of the armor plates to give a finished pavement surface. When the concrete has become hard enough to walk upon, the temporary division plates, if used, are removed and the crevice left is filled with tar or asphalt. Where felt has been employed it may simply be left in place, any subsequent enlargement of the crevice which may possibly occur, being taken care of by pouring in a suitable filler as before.

The above method of laying armored joints is rather troublesome and clumsy and has been found in practice to be more or less unsatisfactory. It has been found that it is almost impossible to get exactly the proper elevation of the upper edges of the armor plates in the manner described. The finished pavement is found as a rule to be either slightly above or below grade at the joints, the result being that the roadway is not perfectly true at all points along its length, but is apt to have regularly recurring ridges or depressions corresponding to the location of the joints. This of course is extremely undesirable and has given considerable trouble heretofore. Moreover the transverse alignment of the joint across the roadway is seldom perfect.

The object of the present invention is to obviate the difficulties heretofore encountered in building concrete pavements having armored joints; and to provide means of comparatively simple character for carrying out the operation of placing these joints with substantially absolute accuracy.

Briefly described, the present apparatus consists of a rigid supporting member adapted to be placed transversely of a roadway and whose shape is advantageously such as to conform to the surface of the finished pavement. This supporting means is provided with any suitable type of gripping or clamping means adapted to engage and hold the upper edges and sides of the armor joint members, and to suspend the same across the roadway at any desired exact elevation corresponding to that required by the elevation of the finished pavement surface. The whole assemblage may conveniently be held by hangers adjustably clamped to the supporting means at the ends thereof. The members which are to form the armored joint are thus held fixedly in position until the concrete is placed around them and properly smoothed off, whereupon the supporting member is removed by releasing the plate-clamping means, leaving the joint plates with their upper edges exactly flush with the finished surface of the pavement. Moreover, owing to the structural rigidity of the supporting device, the armor plates are held in perfect alignment transverse to the roadway.

In the accompanying drawings I have

illustrated a typical embodiment of apparatus elements within the scope of the present invention.

In these drawings, Figure 1 shows the apparatus stretched across a roadway in inverted position and holding the armor plates preparatory to suspending them in final position. Fig. 2 is a plan view of Fig. 1; Fig. 3 shows the apparatus in position holding the armor plates in proper position and at the required elevation across a roadway; Fig. 4 is a transverse section through the supporting bar on a somewhat larger scale showing the details of a typical clamping device; Fig. 5 is a similar section showing a modified form of supporting bar and clamping device; Fig. 6 is a fragmentary view in elevational perspective of a modified form of the apparatus; Fig. 7 is a fragmentary side elevation of another modification; Fig. 8 is a side elevation of apparatus in truss form; and Figs. 9 and 10 are typical completed pavement joints.

Referring to the drawings, 1 is a T-bar curved slightly to conform approximately to the required road crowning and comprising a central vertical web 1^a and horizontal web 1^b, and conveniently provided at each end with an extension 2 by means of which the bar may be suitably supported. It is to be noted that the bar here shown is so curved that its smooth face 3 is on the inner or concave side having the shorter radius. Suitably secured to the T-bar at suitably spaced intervals and projecting from the smooth or flat face thereof are located pegs or clamping abutments 4. Opposite each of these pegs is located an eccentric cam 5 rigidly secured to stud 6, which extends through the horizontal web of the T and is provided on the under side with a fixed hub 7 in which are holes or recesses 8 into which may be inserted a bar for turning the stud and hence the eccentric cam into locking position as shown in full lines in Fig. 4 or into idle or inoperative position as indicated by dotted lines in the same figure. As shown, the stationary peg and its corresponding eccentric cam are best located on opposite sides of the central axis of the T, and on the side opposite to the vertical web. The particular form of clamp shown in Fig. 4 is for use with flat armor plates.

Where the armor plates are of angular cross section, eccentric cams 9 and 10, (Fig. 5) suitably modified to conform to the shape of the bars employed, are provided, both members of the pair being rotatably mounted in this case. The inner or concave side of the bar may also be provided at intervals with projecting lugs 10^a to aid in properly spacing the angular bars and preserving proper alignment thereof.

The method of using the apparatus thus far described is as follows: The T bar is

first placed in inverted position as shown in Figs. 1 and 4 with the clamping means uppermost. Flat armor plates 11 or angular plates 12 are then placed between the clamps with their longitudinal edges, which are subsequently to be flush with the finished pavement surface, substantially in abutment with the inner or concave surface of the bar. Between the bars may be placed 10 paper, felt, asphalt felt, or other suitable spacing material 13, and the cam clamps are then tightened so as to grip the plates firmly. Instead of such spacing material, temporary steel division plates may be used. 15 The T-bar, carrying the clamped armor plates, is then inverted and supported across the roadway in the manner shown in Fig. 3. The points 14, which may be on curbs or side rails, at which the T-bar is supported should be selected or provided so that when the apparatus is in the position shown in Fig. 3, the upper edges of the armor plates are at the exact elevation at which they are required to be in the finished 25 pavement. It will thus be seen that in this position the lower flat face of the bar serves as a gage by reference to which the concrete may be laid to the proper depth. This face also functions as edge-aligning or stop means 30 in the operation of assembling the armor plates therewith as illustrated in Figs. 1 and 4, the wearing edges of the plates being automatically brought into exactly the proper alignment by abutment with said 35 face. When the armor plates have been suspended over the roadway in this manner, the concrete or other pavement material is then placed in position on both 40 sides of the joint and is tamped and packed in closely on both sides of and under the armor plates, and against the spacing material separating the pavement sections. The plates may be provided with projecting 45 prongs or spurs 15 which become embedded in the concrete on the non-adjacent sides of the plates firmly anchoring the plates in position. When this has been done, the clamps gripping the plate edges are loosened by rotating the eccentric cams, the 50 placing device is lifted and removed, and the pavement surface adjacent the armored joint is smoothed to grade in any suitable way, there being generally sufficient excess concrete adjacent the joint to fill in the 55 spaces which were occupied by the clamps and leave the pavement surface exactly flush with the upper edges of the armor plates. If temporary division plates have been used to space the armor plates apart, these may 60 be removed after the concrete is sufficiently hard to walk upon, and the crevices between the armor plates may then be filled with asphalt, tar or the like. Where felt or paper has been employed as the spacing material, this may be allowed to remain per-

manently between the armor plates, and if necessary, tar, asphalt etc., may be also used to insure complete filling of the joint crevices and to secure a perfectly smooth outer surface at the joint. Figs. 9 and 10 70 illustrate typical armor joints obtained by the method just described.

In Fig. 9 the armor members are spaced apart by felt 13 or the like, for which can be substituted tar, asphalt, etc., as stated. In the joint shown in Fig. 10, asphalt or tar 13 is used in conjunction with felt to completely fill the trough-like upper end of the crevice.

Fig. 6 illustrates a modified form of apparatus particularly suitable for use in the construction of concrete roadways on country roadbeds where curbs are not as a rule provided. The T-rail is provided at each end with a depending member 20 suitably recessed or otherwise suitably shaped for engagement with a temporary side rail 21, and spike or stake 22 extends below such recessed member for the purpose of projecting into the ground and temporarily fixing the apparatus in the desired position across the roadway. The T-bar carries clamps as before, and an armor plate 23 is shown suspended in place above a roadway, the earth grade being indicated by line 24. 90

Fig. 7 shows another form which the supporting bar may take. In this instance the T-bar 26, instead of being provided with projecting supporting members at its ends, may be held in place by adjustable clamping means comprising gripping jaws 27 arranged to engage the vertical web of the T-bar, projecting arm 28 being arranged to be supported in any suitable manner, as upon curbs, at the side of the roadway. An 100 adjustable tightening bolt or similar means 29 is provided for tightening or loosening the clamping jaws, thus permitting accurate vertical adjustment of the T-bar in the hanger. 105

Fig. 8 illustrates a somewhat more complex form of supporting apparatus in which a straight upper bar 30 is connected by short braces or struts 31 to a curved bar 32 of flat rectangular section carrying the armor plate clamping means. This gives a truss-like structure of great strength and rigidity which is very useful for some classes of work. The ends of the straight bar 30 may be supported across the roadway 115 by curbs as shown, or by adjustable hangers or other equivalent supporting means. 120

While the supporting bars hereinbefore described are for the most part in the form of T-bars, it is obvious that this particular type of bar is not absolutely essential, although it is extremely convenient. Other shaped sections such as I-beams, channels, and the like, may also be used but are not so advantageous. 130

What I claim is:—

1. Apparatus for constructing armored pavement joints comprising, in combination, a supporting member adapted to be placed over a roadbed and having a lower portion formed to serve as a gage for the finished surface of a pavement to be laid on such roadbed, and means for holding a joint armoring member with its upper or wearing portion in substantial abutment with said lower portion.
2. Apparatus for constructing armored pavement joints comprising a substantially rigid supporting member adapted to be placed over a roadway and provided with means for receiving and suspending joint armoring members over such roadbed during the construction of a pavement with their upper or wearing faces substantially at the exact elevation of the finished surface of the pavement to be laid, said supporting member being shaped to conform approximately to the contour of the finished pavement and being adapted to serve as a gage therefor.
3. Apparatus for constructing armored pavement joints comprising a substantially rigid supporting member adapted to extend transversely of a roadway and provided with means for accurately alining the upper or wearing edges of the joint-armoring plates to be supported thereby, and means on said member adapted to engage such joint-armoring plates and to suspend the same at a predetermined elevation above a roadway.
4. Apparatus for constructing armored pavement joints comprising, in combination, a bar adapted to be placed over a roadway and having a substantially flat lower face, and means for securing a joint armoring member thereto with its upper or wearing edge abutting against said face.
5. Apparatus for constructing armored pavement joints comprising a supporting beam, and clamping means mounted thereon and extending therebelow and arranged to engage and hold joint-armoring means wholly below said beam.
6. Apparatus for constructing armored pavement joints comprising a supporting beam adapted to extend across a roadway and curved to conform approximately to the transverse contour thereof, and a plurality of spaced clamping means mounted on said beam and extending therebelow for suspending joint-armoring members wholly below said beam.
7. Apparatus for constructing armored pavement joints comprising a curved bar, and clamping means arranged on the inner or concaved face thereof for securing joint-armoring members thereto.
8. Apparatus for constructing armored pavement joints comprising substantially rigid supporting means adapted to span a roadway, clamping means carried thereby for engaging the upper edges of a pair of armor plates and arranged in curved alignment corresponding approximately to the required crowning of the finished surface of such roadway, and means for accurately adjusting the height of the assemblage above the roadway.
9. Apparatus for constructing armored pavement joints which comprises a supporting device adapted to be mounted above a roadway and provided with stop means, and means for clamping a joint-armoring member to said supporting device with the upper or wearing edges in abutment with said stop means.
10. Apparatus for constructing armored pavement joints comprising a supporting device having a clamping abutment and an abutment for alining the wearing edge of a joint-armoring member, and means for clamping a joint-armoring member against both said abutments.
11. Apparatus for constructing armored pavement joints comprising a supporting bar provided with clamping means on one face or side thereof for holding armoring members, and means located on another side of said bar for operating said clamping means.
12. Apparatus for constructing armored pavement joints comprising a supporting bar, rotatable eccentric clamping means mounted on one face or side thereof for holding armoring members, and means on an other face of said bar and connected to such rotatable means for operating the latter.
